UNITED STATES PATENT OFFICE.

IDA S. FREEMAN, OF PORTLAND, OREGON.

REMOVABLE-BLADE CUTTING DEVICE.

Application filed February 16, 1925. Serial No. 9,595.

This application is intended as an improvement over my pending application Serial Number 703,209.

My invention is intended for use by 5 clerks, seamstresses, wrappers, and all others who use the same in the regular course of their work, for the cutting of string, cord, thread and the like, and is adapted to be worn upon a finger or thumb of the user 10 of the same.

Further objects of my invention consist in the fact that the main band for mounting the cutting device is adapted to being worn on the finger, and need not be an 15 endless band.

Further objects consist of the method of mounting the blade-holder and guard, for the removable blade.

Further objects consist in a new and 20 novel means for maintaining the cutting and blade holding guard units, in locked position, without the use of screws or other fastenings.

A further object of my invention consists of a one piece split blade-holder and 25 guard and locking means for maintaining the cutting blade therein.

A further object of my invention consists in holding guide-ways being formed 30 from the band material, which are adapted to maintain the blade holder and guard and the blade in frictional relationship therewith.

My invention relies in certain new, useful and novel construction and arrangement 35 of parts as will hereinafter be described. The same is fully illustrated in the accompanying drawings and will be more fully pointed out in the appended claims.

Reference is had to the accompanying 40 drawings, in which—

Fig. 1 is a side elevation of the assembled device.

Fig. 2 is an end view of the mechanism 45 shown in Fig. 1.

Fig. 3 is a plan view of the mechanism shown in Fig. 1.

Fig. 4 is a plan view taken on line 4—4 50 of Fig. 1 looking in the direction indicated.

Fig. 5 is a fragmentary sectional view taken on line 5—5 of Fig. 1 looking in the direction indicated.

Fig. 6 is a perspective view of the blade 55 holding guard and the blade shown removed from the ring.

Fig. 7 is fragmentary side view, partially in section, of the mechanism shown in Fig. 6.

Like reference characters refer to like 60 parts throughout the several views.

1 is the finger engaging band, or ring, made of one piece divided upon the lower portion and having out-turned end terminals as shown at 2 and 3. The purpose 65 of these out-turned end terminals and the construction shown is in order that but one size may suffice for a variety of finger sizes of the users. This construction will minimize the number of sizes of rings that will 70 be required to be made. This construction permits of the expansion and contraction of the band or ring. The band is made with an elongated upper surface, of substantial area, as shown at 4 to form a contacting surface of greater area with the finger of the user. This increased surface contact with the finger is to minimize the pressure exerted upon the ring at the time 75 of the cutting operation with the finger. 80

Struck from the main body of the band are upturned members 5, 6, 7 and 8 formed in such a manner as to create tapering guideways, adapted to holding the blade holder and guard and the blade which is 85 so constructed as to permit of the same being inserted into the tapering guideway. The blade holder and guard 9 is split upon and along its lower portion into two units 10 and 11 to facilitate the insertion of the 90 cutting blade therethrough and its removal therefrom when the same has been removed from the tapering guideway. The blade holder and guard is also split for a portion of its upper length, as shown at 13, which 95 acts for a partial passage of the cutting blade therethrough and to maintain the same in alignment. The upturned end 12 of the blade holder and guard acts as a guide to facilitate the passage of the cord to be cut 100 over the cutting edge of the blade. The guide ways formed from the struck members 5, 6, 7 and 8 are wider at the forward ends than they are at the rear ends and the insertion of the blade holder and guard 9 105 with the cutting blade therethrough and therein has a tendency to force the split portion 10 and 11 inward and to a clasping engagement with the lower portion of the blade 14. The blade holder and guard and the blade are inserted in the guideway as an 110 assembled unit, and in such a manner that

the cutting force exerted has a tendency to force the blade holder and guard and the blade into intimate frictional relationship with the tapering guide way, due to 5 the narrowing up of the guide way in the direction that the blade holder and guard are forced by the cutting energy exerted.

A pressure upon the blade holder and guard 9 in the opposite direction to that 10 of the cutting force and toward the wider end of the tapering guideway will disengage the blade holder and guard and the blade from the guide way and from the band or ring. When removed from the tapering 15 guide way the cutting blade 14 may be removed from the blade holder and guard and a sharp cutting blade reinserted therein.

Having thus described my invention, I 20 wish to make the following claims therefor:

1. A removable blade cutting device comprising a band having an elongated top surface, a tapering guide way struck transversely of the elongated top, a blade holder 25 and guard adapted to receive a cutting blade therein, said blade holder and guard adapted to engagement with the tapering guide way and to maintain the cutting blade in fixed position within the blade holder 30 and guard when inserted in the tapering guideway.

2. A removable blade cutting device comprising a band adapted to being reduced and enlarged, an elongated top surface having a tapering guideway disposed partially 35 across said elongated top surface, a blade holder and guard and a blade adapted to engagement within the tapering guide way, said blade holder and guard and blade adapted to engagement and disengagement 40 from the guide way, and the blade adapted to engagement and disengagement from the blade holder and guard.

3. A removable blade cutting device comprising a flexible band, an elongated top 45 surface formed thereon, a tapering guideway formed on said elongated top surface, a blade holder and guard removably mounted within said guideway, and a blade detachably placed within said blade holder and 50 guard.

4. A removable blade cutting device comprising a contractible and expandible band, having an elongated portion formed thereon, upturned members on said elongated top 55 portion forming a tapered guideway, a blade holder and guard removably positioned within said tapered guideway, and a detachable blade removably maintained within said blade holder and guard.

IDA S. FREEMAN.
